UNITED STATES PATENT OFFICE.

WILLIAM WURDACK, JR., OF ST. LOUIS, MISSOURI, ASSIGNOR TO WURDACK ELECTRIC MANUFACTURING COMPANY, OF ST. LOUIS, MISSOURI, A CORPORATION OF MISSOURI.

ELECTRIC SNAP SWITCH.

Application filed June 3, 1925. Serial No. 34,559.

This invention relates generally to electric switches and, more particularly, to a certain new and useful improvement in electric switches of the so-called snap type.

5 My present invention has for its chief object the provision of an efficient electric snap switch of few co-operating preferably sheet-metal parts which may be cheaply and economically manufactured and which may be 10 readily and quickly operatively assembled with a minimum of time and labor.

My present invention has for a further object the provision of an electric snap switch in which screws or other such means for fastening the members or elements of the switch together are obviated and in which the blades of the switch are "snapped" under the pull of a spring into "on" position, in electrical engagement with the circuit-terminals, and 20 into full "off" position when drawn out of engagement with the line or circuit-terminals, but in which swingable or oscillatory members of the switch are so constructed as to draw, through their inter-engagement, the 25 blades from engagement with the circuit-terminals and thereby assist in actuating the blades of the switch to "off" position.

My present invention has for a still further object to cheapen the cost of manufacture, 30 facilitate quantity production, and simplify the construction of and generally improve upon electric switches of the type described.

With the above and other objects in view, 35 my present invention resides in the novel features of form, construction, arrangement, and combination of parts hereinafter described and afterwards pointed out in the claims.

In the accompanying drawings,

40 Figure 1 is a plan view of an electric snap switch embodying my invention.

Figure 2 is a sectional elevational view of the switch taken on approximately the line 2—2 Figure 1, its blades being, as in Figure 1, in "on" position, that is to say, in electrical 45 engagement with the stationary circuit-terminals.

Figure 3 is a view of the switch, partly in elevation and partly in section, with its blades in "off" position, that is to say, out of electrical engagement with the circuit-terminals.

50 Figure 4 is a similar view of the switch, with its blades likewise in "off" position, but with its actuating handle partly manipulated

preparatory to "snap" actuation of the blades 55 under the pull of the spring of the switch to "on" position; and

Figure 5 is a side elevational view of the switch with its blades moving from "off" to "on" position under the snap-pull of the 60 spring of the switch.

Referring now more in detail and by reference characters to the drawings, which illustrate a practical embodiment of my invention, A designates the base of the switch, 65 which is preferably of any suitable insulation material and which, in practice, may be suitably mounted in a switch box or upon a wall or other support with its outer face flush with the surface of the wall, as is customary. 70

Fixed to and upon the upper face of base A is suitably longitudinally spaced and aligning relation, are pairs of circuit contacts or terminals 1—1 preferably of the spring copper-jaw type, and intermediate the 75 aligning jaws of each pair, base A is longitudinally preferably arcuately cut-away or recessed, as at 2—2, for accommodating the swingable or oscillatory blades of the switch more fully later described.

Disposed or seated longitudinally at its bight or base 3 upon base A intermediate the grooves or recesses 2, with its wall-portions or so-called legs 4—4 presented upwardly, is a frame B of substantially U-shape in end elevation, frame B being preferably constructed by stamping and formed of a single integral section of suitably stiff or rigid sheet-metal. In its base or bight 3, frame B is longitudinally slotted, as at 5, in registration 80 with a third longitudinal and preferably arcuate groove 6 in base A, all for purposes shortly appearing; and at one end of its bight 3, frame B is formed with a preferably integral longitudinal extension 7, which, as 85 well as the opposite end of frame-bight 3 are suitably apertured to accommodate screws or other attaching-members 9 for rigidly fastening frame B operatively to base A. The one longitudinal frame-extension 7 is, as best seen in Figure 1, of such dimensions 90 and so formed to provide outwardly presented oppositely disposed abutments or stops, as at 10—10, for purposes also shortly appearing.

100 The upstanding walls 4 of frame B are cut-away from one side edge in identical configuration, as best seen in Figures 2, 3, 4, and 105

The upstanding walls 4 of frame B are cut-away from one side edge in identical configuration, as best seen in Figures 2, 3, 4, and

5, to provide a pair of so-called edges, as at 11, intermediate their height, in which is formed a pair of relatively shallow horizontally aligning notches 12—12, and suitably 5 at its opposite ends set in or otherwise fixed to the frame-walls 4 adjacent their upper edges and adjacent their uninterrupted side edges, is a re-inforcing cross-piece 13. Formed in the walls 4 adjacent their upper 10 ends and in approximate vertical alignment with the notches 12, are pintle-openings or seats 8.

C designates what may be termed the carrying member for the blades or movable terminals or contacts of the switch, which member is likewise preferably formed by stamping of a single integral section of suitable stiff or rigid sheet metal and comprises a body portion 14 of approximately inverted U-shape and oppositely disposed arms 15—15 extending laterally from the legs of the body 14, as best seen in Figure 1, the body 14 being cut away or otherwise formed upon the inner faces of its legs with a pair of oppositely disposed shoulders 16—16 to rest for oscillation or rocking movement upon the frame notches 12. Fitted and suitably fixed intermediate its ends upon each arm 15 between retaining-washers 17—17 and suitably insulated both 20 from the washers 17 and the arm 15, as shown, is a conducting blade 18, which, it may be added, is of such thickness and dimensions to removably fit between and electrically engage with the fixed contacts or jaws when the switch is in "on" or circuit-closing position, as best seen in Figures 1 and 2, and while the present switch is equipped with two such blades 18, the switch may equally well include a lesser or greater number of such 30 blades as may meet the requirements of any particular installation. At their lower or so-called free ends, the legs of member C are lengthwise extended, as at 19, 19, for engagement in one swung or rocked position of member C with the limiting abutments or stops 10 of frame B, for purposes shortly to appear.

D indicates the manipulative element or so-called lever of the switch, which is also preferably constructed by stamping and formed of a single section of suitably stiff or rigid sheet metal and comprises a central portion or body having the shape or configuration best seen in Figures 2, 3, 4, and 5. 50 As there shown, the body of member D is of so-called skeleton form comprising connected side pieces 20, 21, and upper and lower cross or end pieces 22, 23, respectively. It will be seen, however, that the side piece 21 is 55 obliquely disposed, from lower cross-piece 23 to upper cross-piece 22, to the other side piece 20 and is united to upper cross-piece 22 by an arcuated corner-piece 24, from which it results that the side pieces 20 and 21 are gradually from the lower end to the upper end of

member D spaced farther apart and that member D is correspondingly of greater lateral dimension at and adjacent its upper end than at its lower end. Presented upwardly from body cross-member 22, is an extension 70 25 carrying a suitable actuating handle 26, and projecting downwardly from body cross-member 23, is a tongue 27 fitting and working for engagement with its end walls in the bight-slot 5. Fixed in member D at, and disposed laterally of its upper cross-piece 22, 75 are pintles or trunnions 28.

In assembling the several parts of the switch, member C, having the one or more contact-blades 18 fixed thereupon as described, is 80 preferably first disposed to loosely straddle at its bight the so-called lower cross-piece of member D, which latter member is then fitted upon frame B with its pintles or trunnions 28 in the apertures 8 and its tongue 27 projecting 85 into the bight-slot 5, the walls 4 of frame B being suitably sprung apart to permit the insertion of the oppositely disposed trunnions 28 in their frame-accommodating apertures. A coil-spring 29 is now engaged at one end 90 with the lower cross-piece 23 of member D and at its upper end with the bight or cross piece of member C, and the member C then fitted at its shoulders 16 to rest upon the notches 12 of the walls 4 of the frame B. The switch-proper is then fitted upon and secured as described upon base A, and as so assembled, it will be noted that the member D is suspended at its pintles 28 for rocking or oscillatory movement upon, and intermediate the walls 100 4 of, frame B with its tongue 27 disposed in the slot 5, that the member C is disposed for rocking movement at its shoulders 16 also upon and relatively to frame B, and that the bight of member C is disposed loosely within 105 the body of member D with the side-pieces 20—21 of member D disposed upon opposite sides thereof. It will be noted that the parts of the switch are so relatively constructed that, when the blades 18 are in "on" position, as in Figures 1 and 2, the member C at its bight impinges upon or bears against the one side-piece 20 of member D and that the tongue 27 impinges upon or bears against the one end wall of slot 5 adjacent the frame-stops 10, and that when the blades 18 are in 110 "off" position, as in Figure 3, the opposite side-piece 21 of member D and the bight of member C are in spaced non-engaging relation and that the leg-extensions 19 of member C impinge or bear against the frame-stops 10. 115

The switch as a whole is now ready for use and operation. Assuming then that the switch is in "on" position, as in Figures 1 and 2, lever-handle 26 of member D is manipulated to rock member D, whereupon, through the engagement of member D at its side-piece 20 with the member C, direct positive pressure is first exerted upon member C to disengage its carried blades 28 from the terminals 120 125 130

- 1, and as member C is so rocked and its blades 18 disengaged from the terminals 1, pull is exerted upon the spring 29 and the tension of spring 29 exerted, as soon as the blades 18 are so disengaged from terminals 1, in "snapping" the members C and D and blades 18 to full "off" position, the oscillatory movement of said members to such position being limited by the engagement of the leg-extensions 19 of member C with the frame-stops 10. Thus the force or power required in overcoming the friction between the engaged blades 18 and terminals 1 is delivered under the direct positive engagement between the members C and D, and the spring 28 thus most materially assisted in "snapping" the blades from "on" to "off" position. When the lever-extension 26 of member D is manipulated to actuate the blades 18 reversely or from "off" to "on" position, the members C and D being out of impinging engagement when the blades 18 are in "off" position, as stated, the spring 29, which is gradually extended as the member D is so rocked, solely functions under its pull as member D is actuated to rock member C and "snap" its carried blades into "on" position in engagement with the fixed terminals 1, the rocking movement of the members C and D to "on" position being limited by the engagement of the tongue 27 of member D with said end-wall of the bight-slot 5 of frame B and the tongue 27 of member D also functioning at all times to steady and hold member D from lateral displacement.
- 35 My new switch has been found exceedingly efficient in use and operation. It is compact and durable and composed of few parts, all of which, with the exception of spring 29, are substantially unbreakable and easily and inexpensively manufactured, and the switch as a whole is most readily and conveniently assembled in a minimum of time and with a minimum of labor.
- 45 I am aware that minor changes in the form, construction, arrangement, and combination of the several parts of the switch may be made and substituted for those herein shown and described without departing from the nature and principle of my invention.
- 50 Having thus described my invention, what I claim and desire to obtain by Letters Patent is:
1. An electric snap switch including, in combination, a pair of spaced rigid walls having a pair of aligning bearings, a member mounted upon said bearings for oscillatory movement relatively to the walls, contact-blades carried by said member, a manipulating member supported for oscillation by said walls and comprising a skeleton frame embracing a portion of the blade-carrying member, the manipulating member being adapted for impinging engagement at a side of its frame with the blade-carrying member when said blades are in circuit-closing position, and a coil spring having attachment at its ends with said portion of the blade-carrying member and with the manipulating member for imparting rocking movement to the blade-carrying member upon oscillation of the manipulating member. 70
2. An electric snap switch including, in combination, a slotted base, a pair of spaced rigid walls upstanding from the base and having a pair of aligning bearings, a member mounted upon said bearings for oscillatory movement relatively to the walls, contact-blades carried by said member, a manipulating member supported for oscillation by said walls and having impinging engagement with the blade-carrying member when the blades are in "on" position, a spring having engagement with said blade-carrying and manipulating members for imparting snap rocking movement to the blade-carrying member upon oscillation of the manipulating member, and a tongue upon the manipulating member working in said slot. 75 80 85
3. An electric snap switch including, in combination, a slotted base, a pair of spaced rigid walls upstanding from the base and having a pair of aligning bearings, a member mounted upon said bearings for oscillatory movement relatively to the walls, contact-blades carried by said member, a manipulating member supported for oscillation by said walls and having impinging engagement with the blade-carrying member when the blades are in circuit-closing position, a spring having engagement with said blade-carrying and manipulating members for imparting snap rocking movement to the blade-carrying member upon oscillation of the manipulating member, and means comprising a tongue working in said slot for limiting the oscillatory movements of said blade-carrying and manipulating members relatively to said walls. 90 95 100 105
4. An electric snap switch including, in combination, a slotted base, a pair of spaced rigid walls upstanding from the base and having a pair of aligning bearings, a member mounted upon said bearings for oscillatory movement relatively to the walls, contact-blades carried by said member, a manipulating member supported for oscillation by said walls and having impinging engagement with the blade-carrying member when the blades are in circuit-closing position, a spring having engagement with said blade-carrying and manipulating members for imparting snap rocking movement to the blade-carrying member upon oscillation of the manipulating member, and means for limiting the oscillatory movements of said blade-carrying and manipulating members relatively to said walls, said means comprising abutments on said base, extensions on the blade-carrying member adapted for engagement with said abutments when the blades are thrown to circuit-closing position. 110 115 120 125 130

cuit-opening position, and a tongue upon the manipulating member working in said slot adapted to engage an end-wall thereof when the blades are thrown to circuit-closing position.

5. An electric snap switch including, in combination, a base, a pair of spaced rigid walls having a pair of aligning bearings, a U-shaped member mounted at its legs upon said bearings for oscillatory movement relatively to the walls, the bight of said member being presented upwardly, contact-blades carried by said member, a manipulating member having pivoted connection with said walls for oscillatory movement, said manipulating member comprising a skeleton-frame portion embracing the bight of the blade-carrying member and at a wall thereof having impinging engagement with the blade-carrying member when the blades are in "on" position, a coil-spring having engagement with said blade carrying and manipulating members for imparting snap rocking movement to the blade carrying member upon oscillation of the manipulating member, and means carried by the blade-carrying and manipulating members for co-operation with the base in limiting the oscillatory movements of said members.

30 6. An electric snap switch including, in combination, a pair of spaced rigid walls having a pair of aligning bearings, a U-shaped member mounted at its legs upon said bearings for oscillatory movement relatively to said walls, the bight of said member being presented upwardly, contact-blades carried by said member, a skeleton-shaped manipulating member having pivoted connection with said walls for oscillatory movement and embracing the bight of the blade-carrying member, and a spring having engagement with said blade-carrying and manipulating members for imparting snap rocking movement to the blade-carrying member upon oscillation of the manipulating member, the manipulating member being adapted for impinging engagement with the blade-carrying member when the blades are in circuit-closing position and having non-impinging relation with the blade-carrying member both when the blades are in circuit-closing position and means for limiting the oscillatory movement of said blade-carrying and manipulating members relatively to said walls, said means comprising abutments on the base, extensions on the blade-carrying member adapted for engagement with said abutments when the blades are thrown into circuit-opening position, and a steady tongue upon the manipulating member working in said slot and adapted to engage an end wall thereof when the blades are thrown to circuit-closing position.

55 7. An electric snap switch including, in combination, a slotted base, a pair of spaced rigid walls upstanding from the base and having a pair of aligning bearings, a U-shaped member mounted at its legs upon said bearings for oscillatory movement relatively to said walls, the bight of said member being presented upwardly, contact-blades carried by said member, a skeleton-shaped manipulating member having pivoted connection with said walls for oscillatory movement and embracing the bight of the blade-carrying mem-

ber, and a spring having engagement with said blade-carrying and manipulating members for imparting snap rocking movement to the blade-carrying member upon oscillation of the manipulating member, the manipulating member being adapted for impinging engagement with the blade-carrying member when the blades are in circuit-closing position and having non-impinging relation with the blade-carrying member both when the blades are in circuit-opening position and when the blades are moving to circuit-closing position; and a steady tongue upon the manipulating member working in said slot.

8. An electric snap switch including, in combination, a slotted base, a pair of spaced rigid walls upstanding from the base and having a pair of aligning bearings, a U-shaped member mounted at its legs upon said bearings for oscillatory movement relatively to said walls, the bight of said member being presented upwardly, contact-blades carried by said member, a skeleton-shaped manipulating member having pivoted connection with said walls for oscillatory movement and embracing the bight of the blade-carrying member, and a spring having engagement with said blade-carrying and manipulating members for imparting snap rocking movement to the blade-carrying member upon oscillation of the manipulating member, the manipulating member being adapted for impinging engagement with the blade-carrying member when the blades are in circuit-closing position and having non-impinging relation with the blade-carrying member both when the blades are in circuit-closing position and means for limiting the oscillatory movement of said blade-carrying and manipulating members relatively to said walls, said means comprising abutments on the base, extensions on the blade-carrying member adapted for engagement with said abutments when the blades are thrown into circuit-opening position, and a steady tongue upon the manipulating member working in said slot and adapted to engage an end wall thereof when the blades are thrown to circuit-closing position.

9. In an electric snap switch, in combination, a base, a pair of spaced rigid walls, a U-shaped member mounted at its legs upon said walls for oscillatory movement, contact-blades carried by said member, a manipulating member comprising a skeleton frame having connected opposite end and side pieces, said frame surrounding and embracing the bight of the blade-carrying member having pivot-connection at an end-piece thereof with said walls for oscillatory movement, a coil spring having engagement with the bight of the blade-carrying member and with the opposite end piece of the manipulating member for imparting snap rocking movement to the blade-carrying member upon oscillation of

the manipulating member, and a rigid finger grip-extension projecting from said manipulating member for effecting oscillatory actuations thereof.

- 5 10. In an electric snap switch, in combination, a slotted base, a pair of spaced rigid walls, a U-shaped member mounted upon said walls for oscillatory movement, contact-blades carried by said member, a manipulating-member supported for oscillation by said walls and comprising a skeleton frame surrounding and embracing the bight of the blade-carrying member, a coil spring having engagement with the bight of the blade-carrying member and with the manipulating member for imparting snap rocking movement to the blade-carrying member for oscillation of the manipulating member, and a projecting tongue on the manipulating member working in the slot of the base.

- 20 11. In an electric snap switch, a slotted base, a pair of spaced rigid walls, a first member mounted upon said walls for oscillatory movement, contact-blades carried by said member, a second member supported for oscillation by said walls, a spring having engagement with said first and second members for imparting snap rocking movement to the first member upon oscillation of the second member, and co-operating means upon both said members and the base for limiting the oscillatory movements of said members, said means comprising an abutment on the base, an extension on the first member adapted for engagement with said abutment, and a tongue on the second member working in, and adapted for engagement with an end-wall of, the slot in the base.

- 25 12. In an electric snap switch, a slotted base, a pair of spaced rigid walls, a member mounted upon said walls for oscillatory movement, contact-blades carried by said member, a manipulating-member supported for oscillation by said walls, a spring having engagement with said blade-carrying and manipu-

lating members for imparting snap rocking movement to the blade-carrying member upon oscillation of the manipulating member, and a projecting tongue on the manipulating member working in the slot of the base.

- 50 13. In an electric snap switch, a base, a pair of spaced rigid walls, a U-shaped member mounted upon said walls for oscillatory movement, contact-blades, carried by said member, a manipulating member supported for oscillation by said walls and comprising a skeleton-frame portion embracing the bight of the blade-carrying member, a spring having engagement with the manipulating member and the bight of the blade-carrying member for imparting snap rocking movement to the blade-carrying member upon oscillation of the manipulating member, and co-operating means on the base and the blade-carrying and manipulating members for limiting the oscillatory movements of said members.

- 55 60 65 70 75 80 85 14. In an electric snap switch, a slotted base, abutments on the base, a pair of spaced rigid walls having a pair of aligning bearings, a U-shaped member mounted at its legs upon said bearings for oscillatory movement relatively to the walls, contact-blades carried by said member, a manipulating-member supported for oscillation by said walls and comprising a skeleton-frame portion embracing the bight of the blade-carrying member, a coil-spring having engagement with said blade-carrying and manipulating members for imparting snap rocking movement to the blade-carrying member upon oscillation of the manipulating member, and means comprising abutment-engaging extensions on the blade-carrying member and a tongue on the manipulating-member working in the slot of the base for limiting the oscillatory movements of said members.

In testimony whereof, I have signed my name to this specification.

WILLIAM WURDACK, Jr.
